UNITED STATES PATENT OFFICE.

JOHN V. HORR, OF CLEVELAND, OHIO, ASSIGNOR TO ALBERT T. FISCHER, OF CLEVELAND, OHIO.

CARTON TO SERVE AS RETAINING RECEPTACLE FOR MERCHANDISE.

Application filed April 7, 1920. Serial No. 371,995.

To all whom it may concern:

Be it known that I, JOHN V. HORR, a citizen of the United States, residing at Cleveland, in the county of Cuyahoga and State of Ohio, have invented a certain new and useful Improvement in Cartons to Serve as Retaining Receptacles for Merchandise, of which the following is a full, clear, and exact description.

10 This invention is directed to a carton, or container, which is adapted in its folded condition to serve as a retaining receptacle for merchandise, and is so fashioned, that parts of the same may form an easel, which 15 may be folded into position beneath the body of the container and serve to support the container in inclined position.

Reference should be had to the accompanying drawings forming a part of this 20 specification in which Fig. 1 is a perspective view of a folded carton; Fig. 2 is a perspective view showing carton in open position; Fig. 3 is a transverse section through the body of the carton; Fig. 4 is a longitudinal 25 section through the carton and its easel in open position; Fig. 5 is a longitudinal section through the carton in folded position; Fig. 6 is a perspective view of the carton in 30 partially folded position; Fig. 7 is a plan view of the blank used in connecting the carton.

Referring to the drawings the body of the carton is indicated at 1 and comprises 35 upstanding end members 2 and 3, a rear member 4 and a front member 5. Co-operating with the rear member 4 of the body portion is a member which forms in part a display member and a cover member. This member is formed in two parts, which are 40 indicated at 6 and 7, the members 6 and 7 being secured together part way throughout their length. The members 6 and 7 are detached at their ends, and the member 7 has a tongued portion, which is indicated at 8.

45 At 9 there is generally indicated what I term an easel member. This easel member comprises a bottom portion 10 and upstanding side portions 11 and 12, and a rear portion 13, which is formed by co-operating 50 folds, as later described.

A joining member 14 is hingedly connected at an edge of the bottom member, as in-

dicated at 15 and this joining member 14 has a part 16, which is attached to the bottom of the body portion of the box and there is 55 a score in the member 14 which forms the part 16 so that the joining member 14 may be described as hingedly secured to the bottom of the body portion of the box. The member 14 is formed with a score extending 60 transversely, as indicated at 17, so that the member 14 may fold within the sides and end member of the easel when the carton is in folded position.

A second joining member indicated at 18 65 is hingedly secured to the easel member along the edge, where the rear portion 13 and the bottom portion 10 of the easel meet. This member 18 at its opposite end has a 70 score 19, as indicated in Fig. 6, and a partially cutout tab 20. The end of the member 18, just described is adapted to slide through a slot 21 in the bottom of the body of the carton, and when the end of the member 18 is inserted through the slot the member 18 may be bent along the score 19, whereby the tab 20 engages with the inside of the 75 bottom of the box, beyond the slot 21. This forms a means of securing the joining member 18 to the body of the carton. The joining member 18 is provided with a score 22, as shown in Fig. 4, which permits the member 18 to fold around the end member 13 of the easel, when the carton is in its final 80 folded position.

The member 14 along or adjacent the edge at which it joins with the bottom 10 is provided with an opening 23, which is indicated in Figs. 4 and 6. This slot 23 is adapted to receive the tab 8, which is formed on 90 the cover member 7 when the carton is in folded position. The tab 8 tucks through the slot 23 and so forms a means for maintaining the cover and the easel member in 95 final folded position.

As will be seen more particularly in Fig. 1, when the easel member is folded upon the body of the carton the side members 11 and 12 engage with the outside of the members 2 and 3 of the body of the carton, while the end member 13 of the easel lies parallel with the end member 5 of the body portion, and the bottom member 10 of the easel forms a partial cover for the carton. Therefore, the 100

bottom member 10 of the easel and the cover 7 co-operate to form a complete cover for the carton.

When the carton is open, the easel member 5 is folded around and beneath the bottom member 2 of the body of the carton. This is permitted because of the scores 17 and 22, formed in the joining members 14 and 18. When the easel member is moved to its rear- 10 most position the end member 13 of the easel lies against the bottom member 2 of the carton and this member is held in position by the joining member 18. Under the conditions named, the joining member 14 se- 15 cures what becomes the lower edge of the easel member and holds it in definite position with respect to the body of the carton. In fact, the joining members 18 and 14 both co-operate to hold the easel member in its 20 slanting position as shown in Fig. 2 of the drawings. The member 18 extends along the bottom of the box, while the joining member 14 lies in contact with the surface upon which the carton is supported.

25 The end member 13 of the easel lies between the joining members 14 and 18, and, as before stated, these members are provided with scores, so that the member 14 folds within the easel while the member 18 folds upon 30 the outside of the easel when the easel is moved into position to close the carton.

The blank out of which the carton is made is shown in Fig. 7. The blank is a two part blank, that is to say, one part of the blank is 35 utilized in forming the body part of the carton as well as the display member 6 and the cover member 7, while the other portion of the blank is utilized to make the easel member and the joining members 14 and 18. The 40 blank is preferably made from card board, or similar material, and the portion which forms the bottom 2 of the carton has extensions 2^a and 2^b formed at the sides which fold upon each other to form a double side 45 wall and at the same time the blank is scored so that the double side member may be folded into an upright position with respect to the bottom of the blank 2. The front member of the carton is formed by a scored 50 portion 2^c, which is adapted to fold into an upright position and there are extending tabs carried by these portions which fold inside of the side members to hold assembled end and side members in position. The bot- 55 tom 2 in the blank has an extension at 2^d which is adapted to be folded into upright position and end extending member 2^e which is formed as a part of one of the side mem- 60 bers 2^b that is adapted to extend along the rear end of the box and lie inside of the part 2^a. Each of the side members, such as 2^a is formed with an extension 2^f and 2^g, which members when folded form a part of the back or the rear portion of the body of the 65 carton. Each of these two members 2^f and

2^g is notched as indicated at 2^h and fold into locking position when these two mem- bers 2^f and 2^g are brought together.

The member 2^g is formed as an extension of the cover member 7, which is so formed 70 that when the members 2^f and 2^g are brought together the cover member 7 is in position to co-operate with side walls of the carton to form a cover.

The display member 6 is in part attached 75 or glued to the back member 7 and is scored transversely as indicated at 6^a. The portion of the member 6 which extends below the score 6^a is notched precisely in the same manner as the member 2^g and furthermore 80 this portion of the member 6 which extends below the score 6^a is not secured to the cover member 7. When the member 2^g is assem- bled with regards to the member 2^f, the por- 85 tion of the member 6 which is below the score 6^a, is assembled with it, so that this free portion of the member 6, which is indi- cated at 6^b, is frictionally held between the member 2^g and the member 2^f and fur- 90 thermore the member 6^b is notched, and along 90 with the member 2^g cooperates with the notched member 2^f. This serves to increase the frictional engagement to which the mem- 95 ber 6^b is subjected and thereby increases its ability to be held in a given position when the carton is in its open condition. It will, therefore, be clear that the display member 6 moves with the cover 7, but the position of the display member 6 is controlled by the po- 100 sition of the part 6^b of the display member.

The easel member is formed from a sin- 105 gle blank, the side members 11 and 12 of the easel being formed by bending parts of the blank about suitable scores and the end 13 is formed by two extensions of the side mem- bers 11 and 12, which are locked in position by suitable notches thereby to form a sub- 110 stantial rigid construction.

Having described my invention, I claim—

1. A carton comprising a body portion, an easel having side members, and an end por- 115 tion which joins the side members, a joining member which at one end is hingedly se- cured to the easel and at its opposite end is hingedly secured to the body portion, a sec- 120 ond joining member which is at one end hingedly secured to the easel and its oppo- site end hingedly secured to the body por- 125 tion, the end portion of the easel lying be- tween the said joining members.

2. A carton comprising a body portion, an easel having side members and an end por- 130 tion which joins the side members, a joining member which at one end is hingedly se- cured to the easel and at its opposite end is hingedly secured to the body portion, a sec- 125 ond joining member which is at one end hingedly secured to the easel and at its oppo- site end hingedly secured to the body por-

tion, the first mentioned joining member being adapted to fold inside the easel, and the second mentioned joining member being adapted to fold upon the outside of the easel 5 when the carton is in folded position.

3. A carton comprising a body portion, an easel having side members, and an end portion which joins the side members, a joining member which at one end is hingedly secured to the easel and at its opposite end is hingedly secured to the body portion, a second joining member which is at one end hingedly secured to the easel and its opposite end is hingedly secured to the body portion, 10 the end portion of the easel lying between the said joining members, the first mentioned joining member being adapted to fold inside of the easel and the second mentioned joining member adapted to fold on the outside of the easel and both of said joining members being adapted to fold around the end of the body of the carton 15 when the carton is in folded position.

4. A carton comprising a body portion, 20 an easel having side members and end portion which joins the side members, a joining member which is at one end hingedly secured to the easel and at its opposite end is hingedly secured to the bottom of the body portion adjacent one end thereof, a second joining member which at one end is hingedly secured to the easel and at its opposite end is hingedly secured to the body portion adjacent the connection to the bottom 25 of the body portion of the first joining member.

5. A carton comprising a body portion, an easel having side members and end portion which joins the side members, a joining member which is at one end hingedly secured to the easel and at its opposite end is hingedly secured to the body portion adjacent one end thereof, a second joining member which at one end is hingedly secured to the easel and at its opposite end is hingedly secured to the body portion adjacent the connection of the first joining member, both of said joining members being adapted to fold upon the easel and 45 around the end of the carton, the said easel engaging the end of the body adjacent to which it mounted when the carton is closed. 50

6. A carton, comprising a body portion, an easel having side members, a bottom 55 member and an end portion which joins the side members, a joining member which at one end is hingedly secured to the bottom of the easel and at its opposite end is hingedly secured, adjacent an end of the carton, a second joining member which at one end is secured to the easel at the intersection at the bottom of the easel and end portion of the easel, and at its opposite end is hingedly secured to the body of the 60 carton, the said joining members lying upon 65

opposite sides of the end portion of the easel.

7. A carton, comprising a body portion, an easel having side members, a bottom member and an end portion which joins 70 the side members, a joining member which at one end is hingedly secured to the bottom of the easel and at its opposite end is hingedly secured, adjacent an end of the carton, a second joining member which at 75 one end is secured to the easel at the intersection of the bottom of the easel and end portion of the easel, and at its opposite end is hingedly secured to the body of the carton, the said joining members lying upon 80 opposite sides of the end portion of the easel, the first mentioned joining member being adapted to fold within the easel member and the second joining member being adapted to fold upon the easel member, and both of said joining members being adapted 85 to fold about the end of the body of the carton when the carton is in folded position.

8. A carton comprising a body portion, an easel having side members and an end 90 portion which joins the side members, a joining member which at one end is hingedly secured to the easel and at its opposite end is hingedly secured to the body portion adjacent one end thereof, a second joining 95 member which at one end is hingedly secured to the easel, a slot formed in the bottom portion of the body of the carton, one end of second member extending through said slot, and means for retaining the end 100 of the second joining member with respect to the bottom of the carton.

9. A carton comprising a body portion, an easel having side members and an end portion which joins the side members, a 105 joining member which at one end is hingedly secured to the easel and at its opposite end is hingedly secured to the body portion adjacent one end thereof, a second joining member hingedly secured to the easel, 110 the said second joining member adjacent its opposite end being provided with a folded part and an extending tab, the bottom of the carton being provided with a slot through which the folded end of the second 115 joining member is adapted to extend, the folded portion and the tab of the second joining member being adapted to engage the bottom of the box to retain the second joining member.

10. A display carton having a body portion with engaging folded members which form one wall thereof, said members being notched and held in engagement by co-operation of the notched portions, a cover 125 member hinged to said wall, a display card secured to said cover member and having a depending portion, said depending portion being notched and co-operating with the notched portions of the first mentioned 130

notched members and extending between the said folded members and in frictional engagement therewith.

11. A display carton, having a body portion one wall of which is formed by oppositely disposed members, each of the members adjacent to central portion thereof being provided with re-entrance notches and the members engaging and crossing each

other at the notched portions, a cover member hinged upon said wall, a display card having a depending portion which is notched and co-operates with the notched folded members forming the said wall and is in frictional engagement therewith. 10 15

In testimony whereof, I hereunto affix my signature.

JOHN V. HORR.
